UNITED STATES PATENT OFFICE

2,601,831

CONTROL SYSTEM FOR TRAVELING PLATFORMS

Jean Georges Caillard, Le Havre, France

Application January 9, 1946, Serial No. 640,079
In France September 3, 1940Section 1, Public Law 690, August 8, 1946
Patent expires September 3, 1960

7 Claims. (Cl. 104—50)

1

The travelling platforms generally used in railway stations and engine houses for transferring engines or vehicles from one track to another include a platform provided with rails and adapted to move through the agency of rollers over guideways or races perpendicular to the stationary tracks to be served. Certain of the rollers used therefor are controlled through an electric motor while the other rollers are mounted loose on their axes.

This leads unavoidably to a skidding of the rollers over their races whereby the axes of the rollers do not remain perfectly perpendicular to said races. Moreover, by reason of the comparatively high speed of the platform it is very difficult to stop exactly the carriage at the desired location in order to provide for an accurate register between the rails of the platform and the rails of the stationary tracks to be served.

My invention has for its object a system for controlling traveling platforms whereby it is possible to bring rapidly and accurately the rails of the platform into alignment with the rails of the stationary tracks.

According to this invention, there is inserted between the principal motor of the platform and the control rollers in each side row of rollers a differential mechanism one element of which is connected operatively with an auxiliary motor, which allows bringing slowly the corresponding side of the platform into coaxial relationship with the track to be served.

Such an arrangement of the platform may be associated with a device for stopping automatically the platform exactly in the position of register. To this end the circuit feeding each auxiliary motor includes preferably switches controlled by stationary cams so as to produce the rotation of the auxiliary motors in a suitable direction until concordance is restored.

In accompanying drawing I have illustrated by way of example a form of execution of my invention.

Fig. 1 is a plan view of a traveling platform provided with a control system according to my invention.

Fig. 2 is a corresponding elevational view along line II—II of Fig. 1.

Fig. 3 shows the arrangement for driving the shafts or axes of two oppositely located rollers.

Figs. 4 and 5 show by way of example an arrangement which may be used for the automatic control of the traveling platform. Fig. 4 is an elevational view along line IV—IV of Fig. 1 and Fig. 5 a vertical cross section of the carriage through line V—V of Fig. 4.

2

Fig. 6 is a wiring diagram of the connections of the driving device.

The travelling platform shown in Fig. 1 comprises chiefly two master beams 1 and 2 resting on flanges 3 and 4 provided at their ends with rollers shown at 5, 6, 7 and 8; the rollers 5 and 7 on one hand and the rollers 6 and 8 on the other are adapted to move over races 9 perpendicular to the stationary tracks which are to be served; the frame 11 of the traveling platform carries rails 10, the spacing between which is equal to that of the stationary tracks such as 30, which are adapted to receive the engine or railway carriages or tracks to be transferred from one track to the other.

Two rollers, say rollers 5 and 6, arranged to one side of the beams 1 and 2 on the platform are controlled by a motor while the other rollers 7 and 8 on the other side are mounted loose.

The two rollers 5 and 6 are controlled by a common principal motor 12 resting on an extension 11a of the frame 11 and driving a pulley 13 which is held fast in its inoperative position by means of an electromagnetic brake 13a. This motor drives through the speed reducing gears 14—15 and 16—17 an intermediary shaft 18 carried in the bearings 19 and 20.

Between the shaft 18 and the shaft 22 driving the roller 5 is arranged a differential mechanism 30 including a sunwheel 23 rigid with the shaft 18 and a sunwheel 24 rigid with the shaft 22, said sunwheels 23 and 24 meshing respectively with planet wheels 26 and 25 carried by a rotary cage 27 the bearings for which are shown at 28 and 29 (Fig. 3).

The cage 27 is provided with an outer series of teeth 32 meshing with a pinion 33 keyed to the shaft of an auxiliary electric motor 34 the rotor of which is provided with a pulley 35 adapted to be engaged by an electro-magnetic brake 35a.

The shaft 42 controlling the roller 6 is driven in the same manner through the agency of a differential mechanism comprising a sunwheel 43 fixed on shaft 18, and a sunwheel 44 fixed on shaft 45 42, these sunwheels gearing respectively with satellite pinions 46 and 45, the shafts of which are supported by a rotary cage 47, mounted in bearings 48 and 49.

The cage 47 bears a toothed ring 52 gearing with a pinion 53 keyed on the shaft of an auxiliary electric motor 54, the shaft of which bears a pulley 55 provided with an electromagnetic brake 55a.

The operation of the arrangement is as follows: When the auxiliary motors 34 and 54 are

stopped and held stationary by their brakes while the principal motor 12 is also energized, said motor 12 will drive the intermediary shaft 18. The casings 27 and 47 being held fast, the outer shafts 22 and 42 will be driven through the gears contained in said casings.

The traveling platform progresses then at normal speed over its races 9.

On the contrary, when the motor 12 is stopped and held fast as well as one of the auxiliary motors, such as the motor 34 while the other auxiliary motor alone is operative, the shaft 42 is driven slowly together with the roller 6, which provides for a slow progression of the corresponding side of the traveling platform.

Lastly, if the motor 12 is stopped and held fast by its brake while the auxiliary motors 34 and 54 are controlled either in the same direction or in opposite direction, the rollers 5 and 6 are driven either in the same direction or in opposite directions, so as to produce the slow displacement of each end of the carriage.

It is thus possible to bring each end of the traveling platform in front of the stationary track cooperating with the platform, the auxiliary motors being adapted to drive the corresponding rollers 5 and 6 over the length required for obtaining exact concordance as desired.

The above described system may be provided with a control arrangement for producing the automatic complementary shifting as required for making the ends of the rails 10 of the track carried by the platform register with the rails of the cooperating track. Such an arrangement, shown in Figs. 4 and 5, is provided at each end of the platform.

To either side of the vertical plane of symmetry 0-0 of each stationary track cooperating with the platform are arranged stationary guide-pieces or cams 61 and 62 or 61a and 62a extending in parallelism with the race of the carriage. These cams are carried by brackets 63 and 64 sealed inside the vertical wall 60 or 60a of the pit inside which the platform is adapted to move.

The platform carries a first switch 65 or 65a normally urged into its opening position by a spring or the like means. This switch inserted in the circuit of one of the auxiliary motors 34 or 54 is arranged in a manner such that it may be engaged by the cam 61 or 61a when the platform comes near the position of concordance, so as to provide for the closing of the switch 65 or 65a and to produce the rotation of the motor 34 or 54 in the desired direction.

Another switch 66 or 66a similar to switch 65 or 65a and carried also by the platform is adapted to engage the cam 62 or 62a so as to provide for the energization of the motor 34 or 54 in a direction opposed to the preceding energization.

The operation of this automatic control arrangement is as follows:

The principal motor 12 being stopped and held back for a position of the platform as near as possible, the position of concordance, it may be assumed for instance that at the end of the platform near the roller 5, each of the rails 10 lies at a distance d from the corresponding rail 30 of the stationary track. The distance d being supposed shorter than the length of the cams 61 and 62, the switch 65, coming on the cam 61 is closed, and consequently the closing of said switch 65 thus operated produces the rotation of the auxiliary motor 34 in the direction adapted to make the corresponding end of the platform move in the direction of the arrow F. When the

switch 65 arrives at the extreme end of the cam 61 in front of line 0-0, said switch opens and the motor ceases being fed. Therefore the corresponding end of the platform stops in a position providing for concordance between the rails 10 and the rails 30.

Figure 6 gives the diagram of the electric connections which can be made for operating the motors of the system as well as their locking brakes.

On this diagram, is seen the symbolic representations of the principal motor 12 and the auxiliary motors 34 and 54. Also is seen at 13, 35 and 55 their brake pulleys, and at 13a, 35a and 55a, the corresponding brake mechanisms. Lastly, the cams 61, 62, 61a and 62a, are shown, as well as the end contact breakers of the carriage 65, 66, 65a and 66a.

The current, which is here supposed to be three-phase, necessary for feeding the motors, is first supplied to three mains C₁, C₂ and C₃ by any known means, such as a triple trolley (not shown).

The principal motor 12 is fed in the following manner: three conductors 80, 81 and 82 deriving from the mains C₁, C₂ and C₃, finish at a three-pole contact maker 77, operated by a solenoid 83. When this contact maker is in the closed position, the conductors 80, 81 and 82 are respectively connected up to three conductors 84, 85 and 86 which finish directly at the terminals of the motor 12.

Three other conductors 87, 88 and 89 derived from the conductors 84, 85 and 86 reach a three-pole contact maker 78, operated by a solenoid 90. When this contact maker is in the closed position, the conductors 87, 88 and 89 are connected up to three conductors 91, 92 and 93, respectively connected to the mains C₁, C₃ and C₂, i. e., with inversion of phases with regard to the connections described in the preceding paragraph.

This arrangement means that when the contact maker 77 is closed and the contact maker 78 is open, the motor 12 revolves in one direction, whereas if the contact maker 78 is closed and the contact maker 77 is open, the motor 12 revolves in the opposite direction.

Three other conductors 94, 95 and 96 are permanently connected in derivation on the conductors 84, 85 and 86 which finish at the motor 12. These conductors 94, 95 and 96 feed the three windings of a three-phase electro-magnet 13b whose movable armature is integral to the brake mechanism 13a. This arrangement means that when the motor 12 is fed by closing a contact maker 77 or 78, the electromagnet 13b is excited and its movable armature diverges the brake mechanism 13a from the pulley 13. On the other hand, as soon as the motor 12 ceases to be fed, owing to the two contact makers 77 and 78 being placed in the open position, the electromagnet 13b ceases to be excited and the brake mechanism 13a, released, falls back on the pulley 13 by gravity or under the impulse of a suitable spring, so effectually that not only is the motor 12 stopped, but it is also locked.

It is easy to understand from the diagram that the connections of the auxiliary motors 34 and 54, as well as those of their respective brakes 35a and 55a, are in all points similar to those which have just been described with regard to the principal motor 12 and its brake 13a. In other words, the motor 34 and its brake 35a, are placed under the dependence of two three-pole contact makers 67 and 68, and in like manner, the control of the

motor 54 and its brake 55a, is ensured by the intermediary of two three-pole contact makers 97 and 98. The contact makers 67 and 68 are respectively operated by two solenoids 69 and 70, and the contact makers 97 and 98, by two solenoids 99 and 100.

The six solenoids 83, 90, 69, 70, 99 and 100 are fed with monophase current by the intermediary of a controller 71, hand operated by the carriage operator.

To this end, the solenoids 83 and 90 are, on the one hand, placed in series by a conductor 101, itself permanently connected up to the main C₂ by a derivation conductor 102. On the other hand, the solenoid 83 is connected up by a conductor 103 to a contact piece 104 of the controller 71 and the solenoid 90 is connected up by a conductor 105 to a contact piece 106 of the controller. Lastly, an intermediate contact piece 107 of this controller is connected up by a conductor 108 to the conductor 83, i. e., to the main C₁.

The solenoids 69 and 70 are placed in circuit by a conductor 109, itself connected up by a conductor 110 to a contact piece 111 of the controller 71. On the other hand, the solenoid 69 is connected by a conductor 112 to the contact breaker 65 of which the other terminal is connected by a conductor 113 to the main C₁ and the solenoid 70 is connected up by a conductor 114 to the contact breaker 66 of which the other terminal is connected by a conductor 115 to the conductor 113 and then to the main C₁.

In like manner, the solenoids 99 and 100 are placed in circuit by a conductor 116 itself connected up by a conductor 117 to the conductor 118 and the contact piece 111 of the controller. On the other hand, the solenoid 99 is connected up by a conductor 118 to the contact breaker 65a, whose other terminal is connected by a conductor 119 to the main C₁ and the solenoid 100 is connected up by a conductor 120 to the contact breaker 66a whose other terminal is connected by a conductor 119' to the conductor 119 and then to the main C₁.

Lastly, a last contact piece 121 of the controller is connected up by a conductor 122 to the main C₃.

On the movable cylinder of the controller 71 there are three studs 123, 124 and 125, cooperating with certain of the contact pieces described above, respectively for the positions conventionally indicated by 1, 2 and 3.

The operation of the connections thus described is as follows:

Position 0 of the controller 71: No stud is in contact with the contact pieces, all the circuits of the solenoids of the contactors are open and the three motors 12, 34 and 54 are motionless.

Position 1 of the controller: The stud 123 is in contact with the contact pieces 104 and 107. The excitation circuit of the solenoids 83 is closed and the contact maker 77 is at the closed position; the brake 13a is released and the principal motor revolves in one direction. The traverse carriage moves at high speed on the rails 9 and 9a.

When the carriage reaches the vicinity of the track 30 to be served, one of the contact breakers of each end of the carriage mounts on one of the cams (for example, the contact breaker 65 on the cam 61 and the contact breaker 66a on the cam 62a, which takes place when, for some reason or other, the carriage assumes an oblique position).

The operator then places the controller at the No. 2 position. In this position, the circuits of

the two solenoids 83 and 90 are open, because there is no stud in contact with the contact piece 107. The motor 12 stops and the brake mechanism 13a locks it. In return, as the stud 124 is in contact with the two contact pieces 111 and 121, and as (according to the preceding paragraph) the contact breakers 65 on the one hand and 66a on the other, are in the closed position, the solenoids 69 and 100 are excited and the contact makers 67 and 98 are placed in the closed position. This means that the brake mechanisms 35a and 55a are released and the motors 34 and 54 revolve, one in one direction and the other in the opposite direction, so that the corresponding ends of the platform of the carriage are moved slowly, until the contact breakers 65 and 66a quit their respective cams 61 and 62a, i. e., until the traverse carriage presents both ends of its rails 10 in absolute concordance with the rails of the tracks 30 to be served. At this moment, the contact breakers 65 and 66a open and the solenoids 69 and 100 being no longer excited, the contact makers 67 and 98 return to the open position, so that the motors 34 and 54 stop and are locked by 25 their respective brake mechanisms 35a and 55a.

Position 3 of the controller 71: Only contact pieces 106 and 107 are electrically connected up by the stud 125, the motors 34 and 54 remaining motionless, the solenoid 90 of the contact maker 30 78 is excited and this contact maker placed in the closed position. The brake mechanism is diverted from the pulley 13 and the principal motor 12 is rotated in the opposite direction to that corresponding to position 1 of the controller. The traverse carriage thus returns at high speed towards the position which it previously occupied.

The operator then puts the controller 71 back to position 2, or, if required, to position 0, and so on.

Obviously the different arrangements described and illustrated have been given out solely by way of examples and it is possible in particular to modify the differential mechanisms inserted between the principal motor and the controlled rollers together with the means acting on said differential mechanisms without unduly widening the scope of my invention as defined in accompanying claims.

What I claim is:

1. A traverse carriage for transferring cars from one track to another, comprising in combination, a platform, a section of track fitted on the platform to receive the car to be traversed, rollers supporting the ends of the platform and running on rails perpendicular to the tracks to be served, a principal electric motor, means for positively locking the rotor of this motor, a transmission shaft connected to at least one roller of one end of the platform, a second transmission shaft connected to at least one roller of the other end of the platform; a connecting mechanism comprised between this rotor and each of the two transmission shafts and auxiliary means acting on each of these mechanisms to make these transmission shafts revolve independently of each other and independently of the rotor of the principal motor.

2. A traverse carriage for transferring cars from one track to another, comprising in combination, a platform, a section of track fitted on the platform to receive the car to be traversed, rollers supporting the ends of the platform and running on rails perpendicular to the tracks to be served, a principal electric motor, means for positively locking the rotor of this motor, a transmission shaft connected to at least one roller of one end

of the platform, a second transmission shaft connected to at least one roller of the other end of the platform, a differential mechanism comprised between this rotor and each of the two transmission shafts and auxiliary means acting on each of these differential mechanisms to cause these transmission shafts to revolve independently of each other, after the locking of the rotor of the principal motor.

3. A traverse carriage for transferring cars from one track to another, comprising in combination, a platform, a section of track fitted on the platform to receive the car to be traversed, rollers supporting the ends of the platform and running on rails perpendicular to the tracks to be served, a principal electric motor, means for positively locking the rotor of this motor, a transmission shaft connected to at least one roller of one end of the platform, a second transmission shaft connected to at least one roller of the other end of the platform, a differential mechanism comprised between this rotor and each of the two transmission shafts, an auxiliary electric motor connected to each of the differential mechanisms and means for positively locking the rotor of each of the two auxiliary electric motors.

4. A traverse carriage for transferring cars from one track to another, comprising in combination, a platform, a section of track fitted on the platform to receive the car to be traversed, rollers supporting the ends of the platform and running on rails perpendicular to the tracks to be served, a principal electric motor, an electro-magnetic brake cooperating with the rotor of this motor and arranged so as to come into action as soon as the motor ceases to be fed, a transmission shaft connected to at least one roller of one end of the platform, a second transmission shaft connected to at least one roller of the other end of the platform, a differential mechanism comprised between this rotor and each of the two transmission shafts, an auxiliary electric motor connected to each of the differential mechanisms and an electro-magnetic brake cooperating with the rotor of each auxiliary motor and arranged so as to come into action as soon as this auxiliary motor ceases to be fed.

5. A traverse carriage for transferring cars from one track to another, comprising in combination, a platform, a section of track fitted on the platform to receive the car to be traversed, rollers supporting the ends of the platform and running on rails perpendicular to the track to be served, a transmission shaft connected to at least one roller at one end of the platform, a second transmission shaft connected to at least one roller at the other end of the platform, a principal electric motor, an intermediate shaft operated by the rotor of this motor, a sun pinion fixed at each end of this intermediate shaft, a sun pinion at one end of each transmission shaft, a rotatable cage containing satellite pinions cooperating with each pair of sun pinions, a concentric toothed wheel carried by said cage, an auxiliary electric motor connected to said concentric toothed wheel, and means for individually locking the rotor of each of the principal and auxiliary motors.

6. A traverse carriage for transferring cars from one track to another, comprising in com-

bination, a platform, a section of track fitted on the platform to receive the car to be traversed, rollers supporting the ends of the platform and running on rails perpendicular to the track to be served, a transmission shaft connected to at least one roller of one end of the platform, a second transmission shaft connected to at least one roller at the other end of the platform, a principal electric motor connected to these two transmission shafts for simultaneously moving both ends of the platform, two auxiliary electric motors each connected to one of the two transmission shafts, an electric circuit for making each auxiliary motor to revolve in one direction and a second circuit to make each auxiliary motor revolve in the other direction, a contact breaker inserted in each electric circuit, a fixed cam placed on the course of each contact breaker, opposite each of the tracks to be served, so as to act on this contact breaker and thus cause the corresponding auxiliary motor to revolve, until there is absolute concordance between the section of track of the platform and the track to be served.

7. A traverse carriage for transferring cars from one track to another, comprising in combination, a platform, a section of track fitted on the platform to receive the cars to be traversed, rollers supporting the ends of the platform, and running on rails perpendicular to the tracks to be served, a transmission shaft connected to at least one roller of one end of the platform, a second transmission shaft connected to at least one roller of the other end of the platform, a principal electric motor, an electro-magnetic brake cooperating with the rotor of this motor and arranged so as to lock this rotor as soon as the motor ceases to be fed, an intermediate shaft operated by this rotor, a sun pinion fixed at each end of this intermediate shaft, a sun pinion fixed at one end of each transmission shaft, a rotatable cage containing satellite pinions cooperating with each pair of sun pinions, a concentric toothed wheel carried by said cage, an auxiliary electric motor connected to said concentric toothed wheel, an electromagnetic brake cooperating with the rotor of each auxiliary motor and arranged so as to lock this rotor as soon as the motor ceases to be fed, an electric circuit for making each auxiliary motor revolve in one direction and a second electric circuit for making each auxiliary motor revolve in the other direction, a contact breaker inserted in each electric circuit, a fixed cam placed in the course of each contact breaker opposite each of the tracks to be served, so as to act on this contact breaker and thus cause the corresponding auxiliary motor to revolve, until there is an absolute concordance between the section of track of the platform and the track to be served.

JEAN GEORGES CAILLARD.
